UNITED STATES PATENT OFFICE.

ALBERT E. HUTT, OF PHILADELPHIA, PENNSYLVANIA.

INSIDE STAIRWAY AND FOLDING DOOR FOR DOUBLE-DECK MOTOR COACHES.

Application filed March 5, 1923. Serial No. 622,755.

To all whom it may concern:

Be it known that I, ALBERT E. HUTT, a citizen of the United States, residing at Philadelphia, county of Philadelphia, State 5 of Pennsylvania, have invented a new and useful Inside Stairway and Folding Door for Double-Deck Motor Coaches, of which the following is a specification.

In the conventional double deck motor 10 bus of the character commonly in vogue, there has heretofore been employed an unsheltered outside stairway for permitting the ascent of the passengers to the upper deck, which outside stairway has always 15 been so designed that it took up a great deal of unnecessary room, and in addition being always open to storms and the effects of inclement weather, the steps thereof in bad weather were always open to the effects 20 thereof and were wet or slippery or coated with ice and were very unsafe. This condition has always had a tendency to intimidate passengers from venturing aloft and has tended to a loss of revenue from the reluctance of passengers to take the risk incurred in clambering to the upper deck, particularly if the vehicle was in motion.

For the purpose of obviating the foregoing objectionable conditions, I have devised 30 a novel construction and collocation of enclosed, inside stairway for a motor bus which takes up very little room, is weather proof, and provided with an inside folding door, which folds inwardly into the stair well and 35 preferably against the center stringer, whereby a maximum standing space is provided on the lower deck, and since the stairway is wholly within the vehicle body, it gives the ascending passenger a sense of 40 security and safety and enables the transportation company to sell the upper deck seats more readily, and since the folding doors fold inwardly into the stair well, I am thus enabled to utilize the entire seating 45 and standing capacity of the bus, and particularly provide room for standing passengers on the lower deck by reason of my novel folding door construction.

My novel stairway is so designed and located 50 within the vehicle that the user thereof, upon entering the rear of the bus, walks entirely across the rear vestibule beyond the center aisle line before reaching the folding doors aforesaid and the first or 55 lower stair treads, so that he is entirely within the vehicle before beginning his as-

cent and as the folding doors fold inwardly into the stair well the passenger has ample room to make the ascent, without being impeded by the projecting or folding doors 60 since the latter fold entirely out of his pathway into the stair well.

To the above ends, my invention consists of a winding stairway common to the upper and lower decks, located in a corner of the 65 bus opposite the passenger entrance, so that the end of the aisle of the lower deck intervenes between said entrance and the lower treads, the latter being spaced away from the end of the bus while the upper treads 70 terminate at the upper deck in proximity to said end, in conjunction with folding doors adapted to be folded into the stair well out of the path of the passengers.

It further consists of a novel combination 75 of a winding stairway, a vertical hand rail, a central stringer, a stair door post, a door post and folding doors common thereto and collocated in a novel manner with respect to said stair door post and stringer, so as to 80 fold inwardly against said stringer.

For the purpose of illustrating my invention, I have shown in the accompanying drawings a form thereof which is at present preferred by me, since it will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of the rear end of a motor coach, embodying my 95 invention, showing the rear entrance door open and the doors to the inside stairway folded out of sight in the back of the stair door post.

Figure 2 represents a section on line 2—2 100 of Figure 1, on an enlarged scale, showing the doors in their closed or unfolded position.

Figure 3 represents, on an enlarged scale, a sectional view of the hinge connection 105 common to one of the door sections and the rear of the stair door post.

Similar numerals of reference indicate corresponding parts.

Referring to the drawings:

1 designates the rear end of a motor coach, having the lower deck 2 and the up-

per deck 3, said lower deck having the central aisle 3 and the rear vestibule or platform space 4, in which is the upright stair door post 5, in advance of which is the door post 6, the latter being to one side of the center aisle 3. The stair door post 5 is spaced well away from the rear end 7 of the coach, as will be understood from Figure 2, so that a well defined standing space 8 is afforded and there is also a well defined standing space 9 provided between the door posts 5 and 6. The relative position of the center stringer 10 and the outer stringer 11, and the lower stair treads 12, 13, 14, 15, 16 and so on up, will be understood from Figure 2, whereby a circular or winding stairway is provided, the lower treads being spaced well away from the rear end 7 of the coach, while the upper treads as 16 and 17 terminate in proximity to said rear end and enable the passenger to step out upon the upper deck 3.

Within the center stringer 10 is formed the stair well 18, in which is located the vertical hand rail 19, which extends from the platform 4 upwardly through the upper deck 3, to about the extent indicated in Figure 1, its upper end being deflected laterally as at 20 and then downwardly as at 21.

Especial attention is called to the collocation and arrangement of the folding doors 22, seen in Figure 2, said doors being composed of the sections 23 and 24, hinged together at 25, while the section 24 is secured 35 to the hinged member or leaf 26, which is hinged at 27 to the hinge member 28, which is secured to the inner face of the stair door post 5.

When the door 22 is closed or unfolded, the sections 23 and 24 appear as seen in full lines in Figure 2, the forward end of the section 23 abutting against the door post 6. When the door is open or in folded position, the parts appear as seen dotted in Figure 2, the folded door occupying the space in the stair well 18 intermediate the hand rail 19 and the stair door post 5, and being folded against the center stringer 10. It will be understood that the passenger on entering the rear of the coach walks across the rear end of the aisle 3, and between the door posts 5 and 6 to the lower treads 12 and 13, so that he is entirely within the rear vestibule before he begins his ascent of the stairs, and the door 22 being in open or folded position, affords no obstruction to quick ingress to or egress from the stairs, and in addition permits when folded a maximum amount of room in the space between and in proximity to the posts 5 and 6 for the standing passengers and conductor to stand or move about in. This economizing and utilization of space in the rear of a motor coach of this character is a feature of very great importance in passenger transportation since it enables space that

would otherwise be wasted or occupied by a projecting door to be utilized as above explained.

Having thus described my invention what I claim as new and desire to secure by Letters Patent, is:—

1. In a double deck motor coach, an upper and lower deck, a stairway common thereto, a stair door post spaced away from the lower treads of said stairway, a coacting door post between which access is had to said stairway, and a folding door hinged to said stair door post and adapted when open to abut against the opposite post and when folded to be positioned between the stair door post and said stairway and out of the pathway to the latter.

2. In a double deck motor coach, an upper and a lower deck, a circular stairway common to said decks, a center stringer within which is formed a stair well, a stair door post, a door post forward of the latter, access being afforded between said post to said stairway, and a folding door hinged to said stair door post and adapted when folded to be positioned against said center stringer and to occupy the space within said stair well.

3. In a double deck motor coach, a circular stairway, a center stringer therefor, a stair door post in proximity to said stringer, a door post located in advance thereof, and a folding door having one section hinged to the inner face of said stair door post, and the other section adapted to abut against said door post, said door being adapted to fold against said center stringer in said stair well, so as to be out of the path to said stairway when folded.

4. In a double deck motor coach, an upper and a lower deck, a circular stairway common to said decks and positioned in the rear corner of said coach across the aisle from the rear outer entrance, a center stringer for said stairway, an outer stringer for said stairway, a stair door post positioned in proximity to said center stringer, a door post in proximity to said outer stringer and a folding door hinged to the inner face of said stair door post and adapted to be folded rearwardly against said center stringer and to occupy the stair well within the latter.

5. In a double deck motor coach, an upper and a lower deck, a circular stairway common to said decks and located in the rear end of said coach, a center stringer for said stairway, an outer stringer for said stairway, a stair door post located in proximity to said center stringer, a door post located in proximity to said outer stringer, a vertical hand rail in the stair well formed within said center stringer, and a folding door hinged to the inner portion of said stair door post and adapted to be folded against said center stringer and to occupy the space in said

stair well intermediate said vertical hand rail and stair door posts.

6. In a motor coach, upper and lower decks, a winding stairway common thereto and located in a corner of the bus opposite the passenger entrance so that the end of the aisle of the lower deck intervenes between said entrance of the lower treads, the latter being spaced away from the end of 10 the bus, while the upper treads terminate at the upper deck in proximity to said end, folding doors for said stairway, and means for permitting said doors to be folded into the stair well out of the path of the passengers. 15
